UNITED STATES PATENT OFFICE

WALTER P. SAUER, OF FOREST HILLS, NEW YORK, ASSIGNOR TO THEODOR SAUER COMPANY, OF NEW YORK, N. Y., A CORPORATION OF NEW YORK

EXTENSION TABLE

Application filed February 16, 1929. Serial No. 340,543.

This invention relates to improvements in extensible tables of the type shown in my previous U. S. Patent #1,622,544 dated March 29th, 1927, and has for one of its objects the provision of a table of this character that may be extended and retracted without undue effort.

Another object of the invention is to provide a table of the character referred to that will be positive in action and silent in operation.

A further object of the invention is to provide such a table in which the weight of the table top will rest upon the stationary slide during substantially the entire movement of the slides during the expansion and retraction of the table.

A still further object of the invention is to provide an extensible table in which the parts will so be arranged that the weight of the table top during its downward movement will cause the movable slides carrying the leaves to move inwardly to meet the said table top and form a continuous surface therewith after the said leaves have been extended to a predetermined position.

A still further object of the invention is to provide means for positively limiting the outward movement of the leaves when the table is being extended.

Another object is to produce a device of the character described in which the maximum simplicity of construction and operation is secured.

Other objects and advantages will appear as the nature of the improvements is better understood, the invention consisting substantially in the novel arrangement and co-relation of parts herein fully described, and illustrated in the accompanying drawings, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, there-

fore, is to be understood from an illustrative, rather than a restrictive standpoint.

The inventive idea involved is capable of receiving a variety of mechanical expressions, one of which, for the purposes of illustration, is shown in the accompanying drawings, in which

Figure 1 is a fragmental top plan view of an extensible table showing one embodiment of my invention.

Figure 2 is a sectional view taken on line 2—2 Figure 1 showing the table in normal retracted position.

Figure 3 is a view similar to Figure 2 showing the leaves extended beyond the side edges of the table top and the table top in a position ready to descend to a level with the top of the said leaves.

Figure 4 is a view similar to Figure 3 with the table top in lowered position and the leaves abutting the sides of the table top.

Figure 5 is a similar view to Figure 4 with the leaves extended and the table top raised to a position prior to retraction of the table.

Figure 6 is a cross sectional view of the slide mechanism taken on line 6—6 Figure 1.

Figure 7 is a similar view to Figure 6 showing only one of the movable slides and the positioning of the shoe in the fixed slide taken on line 7—7 Figure 1.

Figure 8 is a similar view to Figure 7 taken on line 8—8 Figure 1.

Figure 9 is a perspective view of the slide shoe stop.

Figure 10 is a perspective view of the shoe and Figure 11 is an inner face view of one of the movable slides.

Referring to the drawings in detail 15 indicates a table supporting frame near one end of which is secured a stationary slide member 16 in operative relation with movable slides 17 and 18. At the bottom of the stationary slide member 16, there is provided a gear G mounted on a stud 19 in a bracket 20 secured to the said stationary slide 16. Secured to the movable slide 17 there is a toothed rack 21 in mesh with the gear G, and a similar toothed rack 22 is secured to the movable slide 18 and in mesh with the said gear G on the opposite side thereof.

The movable slides 17 and 18 are each provided at one of their extremities with a cam plate 22^a normally resting, when the table is in retracted position on rollers 23 rotatably supported on guide brackets 24 secured to opposite ends of the stationary slide 16 and adjacent to the inner surfaces of the movable slides. The said movable slides 17 and 18 are provided with T slots 23^a, and the said slots 10 conform in shape at their ends 24 to the cam plates 22^a. The movable slide 17 has secured thereto a leaf 25 and the movable slide 18 has similarly secured thereto a leaf 26.

A table top 27 overlies the leaves 25 and 26 when the table is in normal retracted position. The said table top is provided with projections 28, which when the table is in the said normal retracted position, rest upon shoes 29 and 30 slidably mounted in guide 20 slots 31 and 32 in the fixed slides 16, and the said shoes are located or positioned by means of pins 33 and 34 in the fixed slide 16 and by means of plates 35 and 36 secured to the underside of the movable slides 17 and 18 respectively.

Upon exerting an outward pull upon one of the leaves, for the sake of explanation, let it be assumed that the leaf 26 is acted upon, then the movable slide 18 will move outwardly, and at the commencement of the said movement the said leaf will drop slightly due to the cam plate 22 and cause a clearance between the bottom of the table top and the said leaf (see Fig. 2). The said clearance will be maintained throughout the entire movement of the movable slide. When the movable slide nears the end of its outward movement, a block 40 (see Fig. 3) will engage the shoe 30 and move same against a stop 41 30 slidably mounted in a vertical slideway 43 and maintained in position by a leaf spring 42 exerting a pressure against the said slide 16 (see Fig. 8). When the shoe is in the position just described, the projection or extension 28 on the table top will be in line with a cutout 44 in the shoe, and the roller 38 will be resting upon the top portion of a cam surface 45 on a cam plate 46 secured to the movable slide 18. The said portion is slightly higher than the surface of the shoe upon which the projection rests.

Due to this cam face and the weight of the table top, the said table top will be lowered by gravity and simultaneously move the 55 movable slide to the Figure 4 position wherein the table top is shown as lowered and the leaf 26 is abutting the lateral edge of the table top 27. The downward movement of the table top will have forced the shoe stop 41 to its lowermost position as shown in Figure 4 and will stay in the said position until actuated by the plate 36 to assume its uppermost position.

To retract the table, the leaf is again 65 pulled outwardly until the roller 38 rests

on the top surface of the cam plate 45 with the post 28 clearing the top of the shoe, and the block 40 again contacts the shoe 30 and moves it against a stop 48 in the stationary slide 16 (see Fig. 5). When in this position, 70 the movable slide and leaf 26 is pushed inwardly and when near the end of the said inward movement, the plate 36 secured to the said movable slide will return the said shoe to its normal Figure 1 position. The said plate 36 will also return the shoe stop 16 to its normal Figure 1 position by pressing against a cam face 50 on the said stop. A bridge plate 51 will maintain the table top in its upper position and prevent same from dropping back into the slot 44 in the shoe during the return of the said shoe from the Fig. 5 position to its normal Fig. 2 position.

It will be understood that both movable slides carrying the leaves 25 and 26 operate 85 simultaneously and the action is the same for both of these leaves as similar parts are duplicated for such action of the leaf 25.

With the arrangement of the parts just described, it will be seen that the table top is supported upon the stationary slide 16 during the entire initial outward travel of the movable slides, that is from the Figure 1 to the Figure 3 position, thus insuring free and easy movement of the said slides during the 95 extension of the table. The only time when the table top is resting upon or exerting a pressure upon the movable slides is when the weight of the table top is causing the slides to move inwardly at which time the 100 operator no longer exerts any pull on the leaf.

The only other time when there is any pressure of the table top upon the movable slides is when the table is being extended 105 prior to retraction, and at that time the rollers 38 are riding upon the cam surface 45 of the cam plates 46, which travel is for a comparatively short distance.

It will be understood that during the initial movement of the slides for expansion, the roller 38 only passes over the top surface of the bridge plate 51 without exerting any pressure thereon, as the said plate will have been lowered by the action of the cam plate 22 on the roller 23 with which it is timed.

The movable slides are guided in their inward and outward movement by means of the guide brackets 24 and by washers 55, the former being secured to opposite ends of the opposite sides of the stationary slides, and the latter being secured to the blocks 40 on the movable slides and fit into respective T slots in the slides.

From the foregoing, it will be seen that I 125 have provided an extensible table adapted for expansion and retraction, in which the parts are so arranged that after the leaves have been extended to a predetermined position with their inner edges beyond the lateral 130

edges of the table top, the table top will force the movable slides to move inwardly as the table top is dropping or riding down to a plane even with the top surface of the leaves. It will also be seen that only a very slight exertion on the part of the operator, will be necessary to operate the said leaves for expansion and retraction as the weight of the table top is supported upon the stationary slide substantially the entire outward and inward movements.

It will also be understood that a similar set of slides having similar operating mechanism is provided at the opposite end of the table.

Having described my invention what I claim as new and desire to secure by Letters Patent is:—

1. In an extensible table, a fixed slide, a movable slide in operative engagement therewith, a leaf secured to the movable slide, a vertically movable table top normally overlying the said leaf, means attached to the fixed slide and a cam on the movable slide, cooperating with said means to provide a clearance between the table top and leaf when the table is being extended.

2. In an extensible table, a fixed slide a movable slide in operative engagement therewith, a leaf secured to the movable slide, a vertically movable table top normally overlying the said leaf, means attached to the fixed slide, and a cam on the movable slide, cooperating with the said means to swing the movable slide and leaf downwardly to provide a clearance between the table top and leaf when the table is being extended.

3. In an extensible table, a fixed slide, a movable slide in operative engagement therewith, a leaf secured to the movable slide, a vertically movable table top normally overlying the said leaf, a shoe slidably mounted on the fixed slide and provided with a cutout, a depending projection on the table top normally resting on the shoe and out of alignment with the said cutout, means on the movable slide to bring the cutout into alignment with the projection at a predetermined point in the outward movement of the said movable slide, a cam on the movable slide, and means on the table top projection in operative engagement with the said cam at the said point of travel to transfer the weight of the table top to the

movable slide to cause the said slide to move inwardly to permit the table top to assume its lowermost position and to abut the leaf.

4. In an extensible table, a fixed slide, a movable slide in operative engagement therewith, a leaf secured to the movable slide, a vertically movable table top normally overlying the said leaf, a shoe slidably mounted on the fixed slide and provided with a cutout, a depending projection on the table top normally resting on the shoe and out of alignment with the

cutout, a vertically slidable shoe stop frictionally maintained in the fixed slide and projecting thereabove, means on the movable slide to engage the shoe to move same against the said stop and position the cutout in the shoe in alignment with the table top projection at a predetermined point of the outward movement of the movable slide, a cam on the movable slide, and means on the table top projection in operative engagement with the said cam at the said point of outward movement to transfer the weight of the table top to the movable slide to cause the said slide to move inwardly to permit the table top to assume its lowermost position and to abut the leaf.

5. In an extensible table, a fixed slide, a movable slide in operative engagement therewith, a leaf secured to the movable slide, a vertically movable table top normally overlying the said leaf, a shoe slidably mounted on the fixed slide and provided with a cutout, a depending projection on the table top normally resting on the shoe and out of alignment with the cutout, a vertically slidable shoe stop frictionally maintained in the fixed slide and projecting thereabove, means on the movable slide to engage the shoe to move same against the said stop and position the cutout in the shoe in alignment with the table top projection at a predetermined point of the outward movement of the movable slide, a second shoe stop on the fixed slide, a cam on the movable slide, and means on the table top projection in operative engagement with the said cam at the said point of outward movement to transfer the weight of the table top to the movable slide to cause the said slide to move inwardly to permit the table to assume its lowermost position abut the leaf and move the shoe stop to a position to permit the shoe to pass to the second stop when the table is extended prior to retraction.

6. In an extensible table, a fixed slide, a movable slide in operative engagement therewith, a leaf secured to the movable slide, a vertically movable table top normally overlying the said leaf, a shoe slidably mounted on the fixed slide and provided with a cutout, a depending projection on the table top normally resting on the shoe and out of alignment with the cutout, a vertically slidable shoe stop frictionally maintained in the fixed slide and projecting thereabove, means on the movable slide to engage the shoe to move same against the said stop and position the cutout in the shoe in alignment with the table top projection at a predetermined point of the outward movement of the movable slide, a second shoe stop on the fixed slide, a cam on the movable slide, means on the table top projection in operative engagement with the said cam at the said point of outward movement to transfer the weight of the table top to the movable slide to cause the said slide to move

inwardly to permit the table top to assume its lowermost position abut the leaf and move the shoe stop to a position to permit the shoe to pass to the second stop when the table is 5 extended prior to retraction, a plate on the movable slide to return the shoe and slidable shoe stop to normal position when the said slide is nearing the end of its retracting movement, and means on the movable slide for 10 bridging the cutout in the shoe during the return to normal position of the shoe.

7. In an extensible table, a fixed slide, a movable slide in sliding engagement therewith, a leaf secured to the movable slide, a 15 table top overlying the leaf, a guide block at one end of the movable slide extending into the fixed slide, a cam at the opposite end of the said movable slide, a bracket on the fixed slide adjacent the cam when the table is in 20 normal retracted position, a guiding extension on the bracket extending into the movable slide, a roller in the extension in engagement with the cam and a base on the bracket clearing the movable slide so as to permit 25 the movable slide to swing downwardly when the table is actuated for extension to produce a clearance between the leaf and table top.

8. In an extensible table, a fixed slide, a movable slide in sliding engagement therewith, a guide block at one end of the movable slide extending into the fixed slide, a bracket on the fixed slide at the end opposite to the guide block, partly extending into the movable slide, means on the said bracket and a 30 cam on the movable slide in operative engagement with the said means to produce a lowering movement of the movable slide when the table is actuated for extension.

9. In an extensible table, a fixed slide, a 40 movable slide in operative engagement therewith, a leaf secured to the movable slide, a vertically movable table top normally overlying the said leaf, a shoe slidably mounted on the fixed slide and provided with a cutout, 45 a depending projection on the table top normally resting on the shoe and out of alignment with the cutout, a stop in the fixed slide normally in spaced relation to the shoe, and a member on the movable slide to engage the shoe to move same against the stop and position the cutout in the shoe in alignment with the table top projection at a predetermined point in the outward movement of the movable slide to position the table top for lowering.

10. In an extensible table, a fixed slide, a movable slide in operative engagement therewith, a leaf secured to the movable slide, a vertically movable table top normally overlying the said leaf, a shoe slidably mounted 60 on the fixed slide and provided with a cutout, a depending projection on the table top normally resting on the shoe and out of alignment with the cutout, a stop in the fixed slide normally in spaced relation to the shoe, a

member on the movable slide to engage the shoe to move same against the stop and position the cutout in the shoe in alignment with the table top projection at a predetermined point in the outward movement of the movable slide to position the table top for lowering, and a cam on the movable slide arranged to cooperate with the table top projection at this point of the outward movement to permit the weight of the table top to be transferred to the movable slide to cause the said slide to move inwardly to permit the table top to assume its lowermost position and abut the leaf.

11. In an extensible table, a fixed slide, a 70 movable slide in operative engagement therewith, a leaf secured to the movable slide, a shoe on the fixed slide, a depending projection on the table top resting solely on the shoe during substantially the entire expansion movement of the movable slide, and means for shifting the shoe out of engagement with the table top projection when the movable slide is nearing the end of its expansion movement to permit the said projection 75 to rest on the movable slide.

12. In an extensible table, a fixed slide, a movable slide in operative engagement therewith, a leaf secured to the movable slide, a shoe on the fixed slide, a depending projection on the table top resting solely on the shoe during substantially the entire expansion movement of the movable slide, means for shifting the shoe out of engagement with the table top projection when the movable 80 slide is nearing the end of its expansion movement to permit the said projection to rest on the movable slide and means for returning the shoe to again support the table 85 top projections when the table is actuated 90 for retraction.

In testimony whereof I hereunto affix my signature.

WALTER P. SAUER.
